UNITED STATES PATENT OFFICE

HENRI CAPDET, OF TOULOUSE, FRANCE

APPARATUS FOR FORMING SINE TRACKS

Original application filed November 29, 1929, Serial No. 410,591, and in France November 12, 1929.
Divided and this application filed November 25, 1930. Serial No. 498,195.

My present application, which is divided out from my pending application No. 410,591 for Letters-Patent of the United States, relates to an apparatus for cutting 5 out tracks of a sine shape on a guide cylinder intended to guide rollers connected to a reciprocating piston, so that when the rollers follow the sine track the reciprocation of the piston is transformed into rotation of a 10 shaft. A transformation of that kind is more fully described in my pending application No. 333,112 for Letters-Patent of the United States.

For cutting out the track on the guide cylinder of the piston use is made of a cam or cams of a circular contour, eccentric on their axes and engaging a flat surface perpendicular to the axis of the cylinder in which the track is to be cut out. The upper bearing 15 surface of the track is cut out on one half of the guide cylinder and the lower bearing surface on another half, the two halves of the guide cylinder being assembled thereafter to form the full track, the embossed 20 portions of the curve on the upper half-cylinder being placed opposite the depressed portions of the curve on the lower half-cylinder, and vice versa.

The object of the present invention is to 25 obtain an apparatus adapted to impart to each half of the guide cylinder above referred to such a motion in respect of a milling tool that a track of sine shape will be cut out therein.

In the accompanying drawing which illustrates diagrammatically by way of example an embodiment of the invention:

Figure 1 is a vertical axial section of the apparatus supporting a half-cylinder.

Figure 2 is a horizontal axial section of the apparatus turned by a quarter of a revolution in respect of the position of Figure 1.

The half-cylinder a , in which the upper or lower surface b , indifferently, of the track is to be cut out, is provided with two plates c d connected integrally with the base r of the half-cylinder by any means such as bolts (not shown). Between these plates rest the cams e e' having a circular contour. Said cams are mounted eccentrically on the axes

f f' bearing the gears for the cams comprised, for instance, of pinions g g' meshing with a central toothed crown h which receives rotation from any motor shaft designated by i . The toothed crown is adapted to rotate 55 with a central shaft j on which a sleeve k will slide while the rotation of the shaft j is imparted to the sleeve k through a tongue l passing in a corresponding groove in said sleeve. The sleeve k is attached, on the one hand, to the half cylinder a and, on the other hand, directly to the plate c and indirectly to the plate d by the intermediary of the base of the half-cylinder a as shown diagrammatically in Figure 2.

The central shaft j serves both to rotate the half-cylinder a by means of the sleeve k and to guide said half-cylinder, while the track surface b is being cut out therein, by means of a shoulder m on the periphery of which the cylinder will reciprocate. On the nose n of the shaft j will fit loosely a bearing portion o (Figure 2) integral with the tool-holder when the latter is introduced into the half-cylinder a in the position shown in the drawing. The tool-holder is of any known type and is provided with any proper gearing adapted to impart rotation to the milling tools p p' . It is supported by any ordinary carriage such as shown at q by its outlines. If it is necessary to grind the surfaces on the half-cylinders after they have been cut out, grinding wheels will be substituted for the milling tools.

The rotation imparted to the motor shaft i 85 is transmitted to the toothed crown h and to the central shaft j , sleeve k and half-cylinder a . The axes of the cams are rotated by the pinions g g' which are rotated by the crown h . The ratio of the speed of the crown h to 90 that of the pinions g g' is equal to the number of reciprocations of the half-cylinder during its revolution. The axes f f' move the eccentric cams e e' in opposite directions. Said cams resting alternately on the flat bottoms 95 of the plates c d cause the sleeve k to reciprocate and consequently also the half-cylinder a . The rotation of the latter, combined simultaneously with the reciprocation of the plates, is such that any point on the axis of 100

the milling tools $p p'$ will describe on the corresponding half-cylinder a fictitious curve the development of which on a plane is a sine curve as will be understood from the above 5 mentioned pending application Serial No. 333,112. During the combined rotation and reciprocation of the half cylinder a the tools $p p'$ only rotate about their axis which is stationary.

- 10 When the two surfaces of the tracks have been thus cut out the two half-cylinders are assembled co-axially to form the full track by the free space left by the cut out portions and the circumferential lag between them 15 must of course be such as to correspond with the number of embossed and depressed portions of the curves on each half-cylinder. The rollers that guide the piston for the conversion of movement as described in my above 20 mentioned co-pending application 333,112 will occupy the same position as the milling tools in relation to the track.

In the above description with reference to the drawing, it will be understood that in Figure 25 1 the eccentrics $e e'$ have moved the half-cylinder a towards the right hand so that the tools seen in end view at p are in contact with the bottom or left hand end of the track that is being cut, whereas in Figure 2 the half- 30 cylinder a having turned by a quarter of a revolution, the eccentrics $e e'$ have moved said half-cylinder to the left and the tools $p p'$ are in contact with the outer end portions of the track.

35 What I claim is:

1. An apparatus for cutting a sine track at the end of a guide cylinder, comprising a tool having a stationary axis and adapted to cut the end portion of said cylinder, in combination with a rotary shaft adapted to rotate the cylinder about its axis, means for causing the cylinder to reciprocate on said shaft, a toothed crown integral with said shaft, two pinions meshing with said toothed crown, two 45 cams having a circular edge and mounted each eccentrically on the axis of one pinion, two plates integral with said reciprocating cylinder, perpendicular to the axis thereof and adapted to bear on the edge of said cams, 50 whereby a sinusoidal movement is given the cylinder while the tool cuts the sine track therein.

2. A machine for cutting a sinusoidal cam surface at the end of a cylindrical piece of 55 work, which comprises in combination, a bearing, an overhung shaft journalled in said bearing, means for causing said piece of work to rotate together with said shaft and allowing it to slide with respect to it, a toothed 60 wheel keyed on said shaft between said bearing and said means, eccentric means, operatively connected with said toothed wheel, for reciprocating said piece of work with respect to said shaft synchronously with the rotary 65 movement of said shaft, a tool having a sta-

tionary axis disposed opposite the end of said piece of work, and means for driving said tool.

3. A machine for cutting a sinusoidal cam surface at the end of a cylindrical piece of 70 work, which comprises in combination, a bearing, an overhung shaft journalled in said bearing, a sleeve slidingly keyed to said shaft and adapted to rigidly support said piece of work, a toothed wheel keyed to said shaft between said bearing and said sleeve, eccentric means, operatively connected with said toothed wheel, for reciprocating said piece of work with respect to said shaft in synchronism with the rotary movement of 75 said shaft, a tool having a stationary axis of revolution disposed opposite the edge of said cylindrical piece of work, and means for driving said tool.

4. A machine for cutting a sinusoidal cam surface at the end of a cylindrical piece of work, which comprises in combination, a bearing, an overhung shaft journalled in said bearing, a sleeve slidingly keyed to said shaft and adapted to rigidly support said piece of work, a toothed wheel keyed to said shaft between said bearing and said sleeve, two circular rollers eccentrically pivoted about stationary axes at right angles to said shaft, 90 means, operatively connected with said toothed wheel, for driving said rollers, a collar secured to said sleeve coaxially with said shaft, another collar adapted to be fixed to said piece of work in parallel relation with the first mentioned collar and at a distance 95 therefrom equal to the diameter of the circular rollers, whereby said rollers are engaged between said collars and are able to cooperate therewith, a tool having a stationary axis of 100 revolution disposed opposite the edge of said cylindrical piece of work, and means for driving said tool.

5. A machine for cutting a sinusoidal cam surface at the end of a cylindrical piece of 110 work, which comprises in combination, a bearing, an overhung shaft journalled in said bearing, a sleeve slidingly keyed to said shaft and adapted to rigidly support said piece of work, a toothed wheel keyed to said shaft be-

tween said bearing and said sleeve, two pinions having stationary axes of revolution at 115 right angles to said shaft adapted to mesh with said toothed wheel, two circular rollers eccentrically mounted on said pinions respectively, in parallel relation therewith, a collar secured to said sleeve in coaxial relation with said shaft, another collar adapted to be fixed to said piece of work in parallel relation with the first mentioned collar and at a distance 120 therefrom equal to the diameter of the circular rollers, so that said rollers are engaged between said collars and can cooperate therewith, a tool having a stationary axis of revolution disposed opposite the edge of said cy- 125 130

lindrical piece of work, and means for driving said tool.

6. A machine according to claim 6 comprising, another shaft in line with the first mentioned one, means for driving the last mentioned shaft, a spindle at right angles to the last mentioned shaft, means for transmitting the rotary movement of said last mentioned shaft to said spindle, two milling tools disposed at either end of said spindle opposite the edge of said cylindrical piece of work, an overhung cylindrical casing forming a bearing for both said last mentioned shaft and said spindle, the free end of said cylindrical casing being adapted to coaxially engage the overhanging end of the first mentioned shaft, and a stop on said first mentioned shaft adapted to cooperate with the ends of said cylindrical casing.

20 In testimony whereof I hereunto affix my signature.
